STRINGING PIN INSULATOR

Arthur W. Ross, Beverly, Mass., assignor to Synthetic Products Manufacturing Corporation, Leominster, Mass.

Filed Mar. 30, 1972, Ser. No. 239,858

Term of patent 14 years

Int. Cl. D13—03

U.S. Cl. D8—230

FIG. 1 is a front elevational view of a stringing pin insulator showing my new design, it being understood that the rear is substantially a mirror image thereof;

FIG. 2 is a right side elevational view thereof;

FIG. 3 is a top plan view thereof;

FIG. 4 is a bottom plan view thereof; and

FIG. 5 is a top, left front perspective view thereof.

I claim:

The ornamental design for a stringing pin insulator, substantially as shown and described.
